Patented Jan. 29, 1974

230,198

COMBINED CAMERA, FILM PROCESSOR, AND PRINTER FOR APERTURE CARDS

Thomas C. Laughon, Rochester, N.Y., assignor to
Eastman Kodak Company, Rochester, N.Y.

Filed July 31, 1972, Ser. No. 276,879

Term of patent 14 years

Int. Cl. D16—03

U.S. Cl. D61—1 Q

FIG. I

FIG. 2

FIG. 1 is a front perspective view of a combined camera, film processor, and printer for aperture cards showing my new design; and

FIG. 2 is a rear perspective view thereof.

I claim:

The ornamental design for a combined camera, film processor, and printer for aperture cards, as shown.
